CLAIM

I claim, the ornamental design for a package, as shown and described.

DESCRIPTION

FIG. 1 is a perspective view of a package, showing our new design in an exemplary embodiment;

FIG. 2 is a front elevation view of the embodiment shown in FIG. 1;

FIG. 3 is a back elevation view of the embodiment shown in FIG. 1;

FIG. 4 is a side elevation view of the embodiment shown in FIG. 1;

FIG. 5 is another side elevation view of the embodiment shown in FIG. 1;

FIG. 6 is a top plan view of the embodiment shown in FIG. 1;

FIG. 7 is a bottom plan view of the embodiment shown in FIG. 1;

FIG. 8 is a perspective view of a package, showing our new design in an exemplary embodiment;

FIG. 9 is a front elevation view of the embodiment shown in FIG. 8;

FIG. 10 is a back elevation view of the embodiment shown in FIG. 8;

FIG. 11 is a side elevation view of the embodiment shown in FIG. 8;

FIG. 12 is another side elevation view of the embodiment shown in FIG. 8;

FIG. 13 is a top plan view of the embodiment shown in FIG. 8; and,

FIG. 14 is a bottom plan view of the embodiment shown in FIG. 8.

The stippling shown in FIGS. 8-14 represents a contrast in appearance.
